Patented Aug. 4, 1914

UNITED STATES PATENT OFFICE

GEORGE H. FORSYTH, OF CHICAGO, ILLINOIS.

SASH CONSTRUCTION.

1,105,970.

Specification of Letters Patent.

Patented Aug. 4, 1914.

Application filed May 11, 1907. Serial No. 373,052.

To all whom it may concern:

Be it known that I, GEORGE H. FORSYTH, a citizen of the United States, residing at Chicago, in the county of Cook and State 5 of Illinois, have invented certain new and useful Improvements in Sash Constructions, of which the following is a specification.

This invention relates to improvements in sash constructions, the several features of 10 improvement being more especially, although not exclusively, applicable to hollow sheet metal sash.

Among the objects of the invention are to produce a tight, dust-excluding, but easily 15 operable sash, characterized by the provision of a relatively large area of dust-excluding contact between the sash and its guide; to provide new and improved means, preferably automatic, for adjusting the sash to 20 variations in width both of the sash-guide and of the sash opening; to provide new and improved means for balancing or supporting the sash in such a way as to tend to maintain the sash centrally of the opening and support the sash equally on both 25 sides; to provide new and improved means for holding the sash when lowered against the sill under tension; to provide new and improved means for releasing both the sash- 30 holding or locking means and the sash-adjusting means; and to provide a new and improved joint for the meeting members of the sash.

To these and other minor ends the invention 35 consists in the novel features of construction and combinations of parts herein-after more particularly described and pointed out in the claims.

The invention will be readily understood 40 when considered in connection with the accompanying drawings showing practical mechanical embodiments of the same, wherein,

Figure 1 is a side elevational view, broken 45 out and partly in vertical section, of a hollow sheet metal sash constructed and equipped in accordance with the present invention. Fig. 2 is a cross-sectional view on the line 2—2 of Fig. 1, looking downwardly. 50 Fig. 3 is a similar cross-sectional view on the line 3—3 of Fig. 1, looking downwardly. Figs. 4, 5 and 6 are detail views in vertical 55 section through the pinch-handle opening of the sash, more particularly illustrating the means for releasing the sash-locking and ad-

justing means from the pinch-handles and maintaining a permanent closure of the pinch-handle opening; and Fig. 7 is a cross-sectional view similar to Fig. 2, illustrating a modification of the sash-adjusting means. 60

Referring to the drawings, 10 may designate as an entirety the upper and lower cross-bars of the sash, and 11 the vertical stiles, which parts may, as herein shown, be pressed or otherwise constructed from sheet metal 65 so as to have a hollow or outwardly-opening channel form.

12 indicates a side post of the frame, to which may be secured the sash-guide, this latter as shown in Figs. 1 and 2 consisting 70 of a pair of suitably bent metal strips 13 having parallel walls 13^a and inwardly turned inclined lips or flanges 13^b.

Referring now to the sash-adjusting means, which means may also tend to hold the sash 75 in adjusted position, and which, as herein shown, are contained within the hollow stiles 11, 14 designates bearing blocks secured to the inner transverse wall of the stile, in which bearing blocks are pivotally mounted on pivot-pins 15 a series of thrust-members each consisting of a pair of parallel short links 16 lying in the plane of the sash, on the outer ends of each of which links are pivotally hung a pair of adjusting strips 17. 80 These latter are formed, as most clearly shown in Fig. 2, with wedge-shaped outer margins that are adapted to be guided between the straight and inclined walls 13^a and 13^b of the sash-guide when said strips 90 are raised, the action of which is to thrust or force the side walls of the stile into a snug dust-excluding contact with the parallel side walls of the guide, and also to force the inclined or beveled edges of the adjusting strips into similar snug dust-excluding contact with the inclined lips or flanges 13^b of the guide, thus affording a relatively large 95 and extended area of dust-excluding contact. This action also tends to crowd the 100 sides of the sash into snug engagement with the guides so as to partially or wholly support the sash and also to adjust the sash laterally of the opening as well as transversely of the guides. In effecting these re- 105 sults I also employ means for producing normally a lifting or supporting tendency on the thrust-members 16 and, incidentally, to some extent a lifting or supporting tendency on the sash itself, which means may 110

consist of a tape or cord 18 secured at one or both ends to a suitable sash-balance (not shown) and passing around and beneath the pulleys 19 mounted in the upper ends of vertical extensions 20 of the upper pair of thrust-links 16 on either side of the sash. To transmit this tendency from the upper pair of thrust-members to the series lying therebelow, as also to effect the release of the adjusting means when desired to raise the sash, I have herein shown a rod 21 that passes through swiveled bearing blocks 22 mounted in and between the thrust-links 16 of each pair, said lifting rod having cotter or stop pins 23 extending therethrough suitably engaging the bearing-blocks 22; and the lower end of the rod 21 on each side having a pivotal link connection 24 with a releasing lever 25. This latter is pivoted intermediate its ends on a suitable pivot-pin extending between the side walls of the lower bar of the sash, such a pin being shown at 26 and at its inner end threaded into a washer 27 that may be riveted in the rear wall of the sash-bar as indicated at 28.

In the bottom of the sash is slidably mounted between guides 29 and 30 independently secured to the opposite side walls of the sash, so as not to interfere with the transverse resiliency of the side walls of the stile, a plunger 31, the outer end of which is tapered or inclined on its upper side, as shown at 32 to fit beneath a correspondingly-shaped undercut of the guide flanges 13^b, said plunger being normally pressed into locking position by a compression spring 33 confined between the inner end of the plunger and a stop 34 on the lower wall of the sash-bar. The inner end of the plunger has an upwardly projecting contact lug 35 adapted to be engaged for the retraction of the plunger by the depending arm 36 of a bell-crank lever, the hub 37 of which is pivotally mounted on the pivot-pin 26 that carries lever 25, while the inwardly extending arm 38 of the bell-crank lever is provided with a laterally projecting thumb-piece 39 extending through an arc-shaped slot 40 in the side wall of the sash-bar and cooperating with a stationary pinch-handle or finger-piece 41 riveted to the side wall of the sash-bar directly above the opening. The arm 38 of the bell-crank is further provided with an inwardly projecting lug 42 (Fig. 3) lying beneath the inwardly projecting arm of lever 25, which latter stops short of the transverse plane of the opening 40 and overlies the path of movement of the lug 42. From the foregoing it will be seen that when the pinch-handles 39 and 41 are compressed, the bell-crank is first moved to carry its depending arm 36 into engagement with the contact-lug 35 of the plunger; on the further closing movement of the pinch-handles the plunger is withdrawn from be-

neth the guide-flanges 13^b, at which time the lug 42 reaches and strikes the inwardly projecting arm of lever 25, thereby raising said arm and consequently depressing the outer arm and the releasing rod 21, which retracts the adjusting strips 17 and thus releases the hold of the sash on its guides whereby it may be easily slid up and down. The steps last described in connection with the compressing of the pinch-handles 39 and 41 are well illustrated in the detail views Figs. 4, 5 and 6; in connection with which latter I have further shown the inner arm of the bell-crank as provided with a vertical plate 43 of somewhat greater width than the slot 40, as shown in Fig. 1, and of sufficient height to cover the opening in all positions of the pinch-handles.

In order to prevent the possibility of the thrust-members 16 from passing beyond the horizontal position, any suitable stop device may be employed, such devices being herein illustrated as stop-blocks 44 (Fig. 1) riveted to one or both sides of the sash stile just above the thrust-members so as not to interfere with the transverse resiliency of the side walls of the sash stile. In this connection I may state that the side walls of the sash stile may or may not be so formed as, when inserted in the guide, to exert a lateral pressure against the walls of the guide under their own resiliency.

In Fig. 7 I have illustrated a modification of the sash-adjusting means, wherein I have shown a plain channel-shaped guide-strip 45 secured to the post or side wall of the casting within which guide are a pair of inversely disposed vertical strips 46 of triangular form in cross-section, with their oblique sides outwardly convergent, thus forming a wedge-shaped groove between them; and I have shown pivoted to the ends of the thrust-bars 16 an adjusting-strip 47 having a corresponding wedge-shaped outer edge adapted to engage the wedge-shaped groove 46 or channel formed by and between the strips 46. The strips 46 may be vertically stationary, or they may be vertically movable with the sash, as shown, being connected to the latter by pins 46^a engaging transverse slots 11^a in the sides of the sash stile to permit the necessary in and out play of said strips 46. In connection with Fig. 2 I may also mention that while I have shown the guiding flanges or lips 13^b as elastic strips integral with the guides 13, obviously they might be separate from the guides 13 or might be replaced by a solid or rigid bevelled strip affording inclined and abutting surfaces for the adjusting-strips 17. The strips 46 and 47 may be resilient, consisting of hollow or elastic material. Furthermore, the adjusting-strips 17 and 47 may, if desired, be outwardly bowed intermediate their ends to insure the outward pressure 130

thereof between the thrust-links, as well as at points coincident with the ends of the latter.

In Fig. 1 I have shown a further feature 5 of improvement consisting of a novel joint between the vertical and transverse side wall members of the stile and bar, respectively, at the corners of the sash, the same consisting of a dovetailed projection 10^a fitting a 10 correspondingly shaped notch 11^b in the adjacent edge of the side wall of the stile, the two being preferably welded together. The leading advantages of this construction reside in the fact that it not only affords a 15 flush outer surface to the entire sash, but also avoids double thickness of metal and increases the strength.

I claim:

1. The combination with a hollow metal 20 sash and sash-guide, of an adjusting strip, contained within the sash, one or more links pivotally connecting said adjusting strip to the sash whereby said adjusting strip is thrust outwardly upon a relative movement 25 between the sash and adjusting strip, and means coöperating with said adjusting strip to effect a snug contact with a side wall of the guide in any adjusted position of said sash.

2. The combination with a hollow metal 30 sash and sash-guide, of an adjusting strip, contained within the sash, one or more links pivotally connecting said adjusting strip to the sash, means normally tending to create 35 a relative vertical movement between said sash and adjusting strip whereby the latter through said links is thrust outwardly into engagement with the guide, and means coöperating with said adjusting strip to secure 40 snug contact with a side wall of the guide in any adjusted position of said sash.

3. The combination with a hollow metal 45 sash and sash-guide, of an adjusting strip, contained within the sash, a plurality of links pivotally connecting said adjusting strip to the sash, means normally tending to create 50 a relative vertical movement between said sash and adjusting strip whereby the latter through said links is thrust outwardly into engagement with the guide, and means carried by the sash for positively operating said links in a manner to retract said adjusting strip from the guide.

4. The combination with a sash and sash- 55 guide, of an adjusting strip, a plurality of links pivotally connecting said adjusting strip to the sash, means normally tending to create a relative vertical movement between said sash and adjusting strip whereby the 60 latter through said links is thrust outwardly into engagement with the guide, a spring-pressed locking plunger for the sash, and means operating to first retract said locking plunger and subsequently retract said ad- 65 justing strip from the guide.

5. The combination with a hollow metal sash and sash-guide, of an adjusting strip, contained within the sash, a plurality of links pivotally connecting said adjusting strip to the sash, means exerting a continuous lifting 70 effect on said adjusting strip, and manually operable means carried by and attached to said sash for overcoming said lifting effect.

6. The combination with a sash and sash- 75 guide, of an adjusting strip, a plurality of links pivotally connecting said adjusting strip to the sash, means exerting a continuous lifting effect on said adjusting strip, a locking plunger for the sash, and manually operable means for first retracting said lock- 80 ing plunger and subsequently overcoming said lifting effect on said adjusting strip.

7. The combination with a sash and sash- 85 guide, of an adjusting strip connected to the sash through means whereby said strip may be moved toward the sash-guide, said adjusting strip having a beveled edge, and a strip carried by the sash having a beveled edge co-operating with the beveled edge of said adjusting strip to force the sash into snug en- 90 gagement with the guide.

8. The combination with a sash and sash- 95 guide, of an adjusting strip connected to the sash through means whereby said strip may be moved toward the sash-guide, said ad- justing strip having a beveled edge, and a strip carried by the sash and capable of bodily lateral movement relative thereto, said last-named strip having a beveled edge co-operating with the beveled edge of said 100 adjusting strip to effect a snug fit of the sash in the guide both in the plane of and trans- versely of the sash opening.

9. The combination with a sash and sash- 105 guide, of an adjusting strip pivotally connected to the sash and adapted to cause en- gagement of the latter with the guide, and means associated with said adjusting strip for actuating the latter to effect edgewise alinement of said sash, substantially as de- 110 scribed.

10. The combination with a sash-guide, of a sash having a hollow stile formed with side walls relatively elastic in a transverse direction, means pivotally connected to the 115 sash for effecting a snug engagement of said side walls with the side walls of the guide, and means for releasing said snug engage- ment when the sash is to be moved.

11. The combination with a sash-guide, of a sash having a hollow stile formed with lat- 120 erally movable side walls, means pivotally connected to the sash for effecting a snug en- gagement of said side walls with the side walls of the guide, and means for releasing 125 said snug engagement when the sash is to be moved.

12. The combination with a sash-guide, of a sash having a hollow stile formed with laterally movable side walls, means pivot- 130

ally connected to the sash and located within said hollow stile for effecting a snug engagement of said side walls with the side walls of the guide, and means for releasing 5 said snug engagement when the sash is to be moved.

13. The combination with a sash guide, of a sash having a side normally engaging said 10 guide under pressure, said side having an auxiliary member with a portion inclined to the plane of the sash, and a movable adjusting member coöperating with said inclined portion of said auxiliary member in varying the pressure of the sash upon the guide, 15 substantially as described.

14. The combination with a sash guide, of a sash having a side normally engaging the 20 guide under pressure, said side having an auxiliary member with a portion inclined to the plane of the sash, and an adjusting member pivotally connected to the sash and co-operating with said inclined portion of the auxiliary member in varying the pressure of the sash upon the guide, substantially as described. 25

15. In a window construction, the combination of a sash guide, a sash engaging said 30 guide, wedging means between said sash and said guide and having a bearing surface substantially co-extensive with the height of the sash, a balance connected with said wedging means, whereby the former is held in any adjusted position, and equalizing means connected with said balance, whereby the 35 sides of the window sash are kept in horizontal alinement, substantially as described.

16. In a window construction, the combination of a sash guide, a sash engaging said 40 guide, wedging strip between said sash and said guide and extending substantially the full length of the sash, a balance, connecting means between said balance and said wedg-

ing means, and equalizing means mounted on said sash and associated with said connecting means, whereby the sash is kept in 45 horizontal alinement, substantially as described.

17. The combination with a hollow metal sash having expansible walls, of an adjusting strip located therein, and means coöperating with said adjusting strip to expand the walls of the sash to effect a snug engagement between the sash and guide, and means for relieving said engagement, whereby the sash may be raised and lowered, substantially as described. 55

18. The combination with a hollow metal sash having expansible walls, of an adjusting strip contained within the sash and extending substantially the full length thereof, 60 and means coöperating with said adjusting strip to expand the walls of the sash to effect a snug lateral engagement between the sash and the guide walls, substantially as described. 65

19. In combination with a window frame, a sash within said frame, counter-balancing means connected with said sash, means for releasing the action of said counter-balancing means on said sash, and means for increasing the frictional engagement between both sides of said sash and said frame, substantially as described. 70

20. In combination with a window frame, a sash within said frame, counter-balancing means connected with said sash, and means connected with said counter-balancing means for effecting close engagement between both sides of the sash and the frame, substantially as described. 75

GEORGE H. FORSYTH.
